United States Patent Office

Des. 233,832
Patented Dec. 3, 1974

233,832

TENNIS COURT FLOORING UNIT OR THE LIKE

Jean Becker, 13 Avenue de la Gare,
Soissons, France

Filed July 25, 1972, Ser. No. 274,866

Term of patent 14 years

Int. Cl. D25—02

U.S. Cl. D13—1 J

FIG. 1

FIG. 2

FIG. 4

FIG. 3

FIG. 5

FIG. 1 is a plan view of a ground covering showing my design;

FIG. 2 is an edge view thereof;

FIG. 3 is another edge view thereof;

FIG. 4 is a bottom plan view thereof; and

FIG. 5 is a perspective view thereof.

I claim:

The ornamental design for a tennis court flooring unit or the like, substantially as shown.
